TYPEWRITER ATTACHMENT

William Smith, Winthrop, Mass.

Application October 25, 1933, Serial No. 695,137

3 Claims. (Cl. 197—126)

The object of the present invention is the provision of a typewriter attachment to facilitate the making of manifold copies of invoices and the like.

5 In the drawing which accompanies and forms a part of this specification—

Figure 1 is an end view of a typewriter attachment embodying my invention;

Fig. 2 is a section taken on the line 2—2 of 10 Fig. 3;

Fig. 3 is a plan view;

Fig. 4 is a fragmentary side view on an enlarged scale.

In the particular drawing selected for more 15 fully disclosing the principle of my invention, 10 represents a frame of any suitable construction which is removably attachable to the carriage of a typewriting machine, the side rails of which carriage are indicated in the present instance at

20 A, A. In the particular form illustrated in the drawing the removably attachable frame comprises a telescopic front bar 12 substantially co-extensive with the length of the carriage and a rearward extension 11.

25 While the two portions of the frame are illustrated as each adjustable longitudinally to accommodate the frame to carriages of different lengths, it is to be understood of course that this is not essential and that the carriage may be 30 made of fixed or non-adjustable length, the length of the carriage in each instance being determined by the machine with which my attachment is to be used. In sliding engagement with the front bar are two end members 13, 13 each held in adjusted position by the set screws 14, 14.

The rearward extension aforesaid consists of a 35 pair of contiguous rods 15, 16 in parallel relation to each other, each of said rods having an end portion 17 bent at right angles to itself to form an eye 18 through which the other rod passes. The forward ends of the end portions 17 aforesaid are secured to the front bar in any suitable manner, as for example, by means of the nuts 19, 19 threaded to said end portions and disposed on either side of the slidable members 13.

40 A paper guide consisting of a pair of fingers 20, 20 of any desired form is adjustably attached to the rearward extension by the set screws 21, said fingers being in slidable engagement with the rods 11.

Secured to the front bar 12, as by brazing or otherwise, is a socket 22 adapted to receive a rearwardly-inclined telescopic paper support, the latter being held in said socket by the set screw 45 55 23. In the present instance the paper support

consists of a hollow polygonal rod 24 and a rod 25 of similar cross section slidable therein. In the drawing both rods are shown as square, although it will be obvious that they might be triangular or of any other suitable cross section.

5 As shown in Figs. 1 and 2 the upper end of one side of the hollow rod is slotted to form the leaf-spring 26. Preferably the rearward side of the upper end is so slotted. A nut 27 is brazed to said leaf-spring and a screw 28 is in threaded engagement with said nut, said screw passing through the leaf-spring and having its end in engagement with the rod 25. By this means the frictional engagement of the upper with the lower rod may be modified. It is to be understood of course that any other suitable means may be employed for this purpose.

The upper end of the front side of the rod 25 is slotted to form the leaf-spring 29 and a cap 30, of any suitable construction, is pivotally connected to the rod 25, as indicated at 31. The cap is provided with a leaf-spring 32 extending downwardly over the spring 29. By means of the screw 33 having threaded engagement with the nut 34 brazed to said cap, the inner end of said 25 screw passing through the cap and engaging the rod 25, said cap may be rocked about its pivot to vary the pressure of the spring 32 on the spring 29.

It will thus be seen that the leaf spring or 30 spring finger 32 is normally in engagement with the front side of the paper support 25, the leaf spring 29 being integral with said support.

A pressure arm 33' may with advantage be employed to press the paper slightly against the 35 paper support. The arm 33', if used, may conveniently be pivoted to the bracket 34 projecting from the forward side of the cap 30. In the present instance the upper end of said arm 33' is bent at right angles to itself and passes through a 40 socket in said bracket, as indicated at 35.

The rearwardly-extending ends 13 of the front bar of the frame may conveniently be attached to the side rails A of the typewriter carriage by screws 36 passing through the bifurcated ends of 45 the members 13 and having threaded engagement with said rails.

The operation of my attachment is as follows:

50 Invoices and the like are made up in strips, each consisting of a large number of invoice blanks, the several blanks being separated by scoring, perforating, or in any other suitable manner. Superimposed on each invoice original are blanks for manifold copies, such as ledger copies, package slips, shipping copies and the like. Between the 55

blanks at the end of the strip of blanks are placed sheets of carbon paper, the ends of which project about an inch on either side of the blanks.

A strip of blanks is indicated at 48 in Fig. 2. 5 The strip is threaded through the guide 28, 29, under the platen 41 of the typewriting machine and up over the front bar 42 of the frame into position for typing the first invoice. As soon as 10 the typing of the first invoice has been completed, the operator grasps the strip of blanks by the upper corners thereof and draws the same up over the paper support and into engagement with the clip formed by the springs 29, 32. The operator then releases the spring which in all typewriting 15 machines holds the paper in frictional engagement with the platen and grasping the protruding ends 42, 42 (Fig. 3) of the carbon paper, draws the latter downwardly and under the platen, so that the same is in position for typing the second invoice and the copies thereof.

The spring aforesaid is then set to press the paper against the platen, the upper end of the first invoice and the copies thereof are removed from the clips 29, 32 and severed from the strip of invoice blanks along the perforated or scored portions aforesaid. The second and following invoices and the carbon copies thereof are then typed successively until the strip of invoice blanks has been used, the procedure above outlined being 30 repeated in the case of each of said blanks. In Fig. 4 I have indicated at 48 a portion of a strip of invoice blanks and the interleaved carbon sheets in the position occupied after the first invoice has been typed and the same with the manifolds held between in the spring clip 29, 32. It 35 will be noted that the upper edges 44 of the carbon sheets terminate short of the spring clip so that when the pressure between the paper and the platen is released the carbon sheets can be drawn downwardly into co-operation with the second blank. The lower edges of the carbon sheets are indicated at 45.

While I have described a particular form of my invention with some detail it will be understood of course that various changes may be made in the particular apparatus disclosed without departing from the scope of the invention hereinafter 5 claimed. I claim:

1. A typewriter attachment comprising in combination a frame removably attachable to the carriage of a typewriting machine, said frame comprising a telescopic front bar substantially co-extensive with the length of the carriage, a pair of contiguous rods in parallel relation to each other, each of said rods having its end portion bent at right angles to itself to form an eye, means attaching said end portions to the ends of said 15 bar, each said rod passing through the eye of the other, and a paper guide secured to the parallel portions of said rods.

2. A typewriter attachment comprising in combination a frame removably attachable to a typewriting machine, a rearwardly-inclined paper support secured to said frame intermediate the ends thereof, the upper end of said support being slitted to form a leaf spring, a cap pivotally connected to said upper end, a leaf spring secured to 25 said cap and extending downwardly over the leaf spring first mentioned, and means for rocking said cap about its pivot to vary the degree of contact between said leaf springs.

3. A typewriter attachment comprising in combination a telescopic frame adjustable to be substantially co-extensive with the length of the carriage of a typewriting machine, said frame being composed of extensible front and rear elements disposed in substantially parallel relation, means 30 for removably attaching said frame to said carriage, a paper guide carried by the rear element of said frame, a socket secured to the front element of said frame substantially midway between the ends thereof, and a rearwardly inclined paper 35 support removably secured in said socket.

WILLIAM SMITH.
